UNITED STATES PATENT OFFICE.

NICHOLAS S. VEDDER AND FRANCIS RITCHIE, OF TROY, NEW YORK, ASSIGNEES TO NICHOLAS S. VEDDER.

DESIGN FOR A HEATING-STOVE.

Specification forming part of Design No. 5,157, dated August 1, 1871.

To all whom it may concern:

Be it known that we, NICHOLAS S. VEDDER and FRANCIS RITCHIE, each of the city of Troy, in the county of Rensselaer and State of New York, have jointly invented and produced a new and original Design for Stoves, of which the following is a specification, reference being had to the accompanying photographic representation of a stove having our said design.

One part of our invention is the design for the urn N, composed of the body o and bail-work p, all shaped and arranged together and ornamented so as to appear substantially as represented in the accompanying photograph. Another part of our invention is the design for the urn-base Q, shaped and ornamented as shown in the photograph. Another part of our invention is the design for the cover R, as distinguished by the rows of ornaments s and t, all shaped and arranged together on the curved surface of the cover so as to appear as represented in the aforesaid photograph. Another part of our invention is the design for the top rim U, as characterized by the rounded edge v and row of ornaments w, shaped and arranged on the surface of the rim as shown in the photograph. Another part of our invention is the design for the upper section X, as distinguished by the upright rows of ornaments y, shaped and arranged upon a plaid or horizontally and vertically-grooved ground so as to present substantially the same appearance as is shown in the aforesaid photograph. Another part of our invention is the design for the rim Z, as distinguished by its rounded edge a and the rows of ornaments b, shaped and arranged on the curved surface of the rim, as shown in the photograph. Another part of our invention is the design for the door-frames C, as distinguished by the ornament d arranged around the curved-top illuminating openings in the doors, and the scroll-piece e, all shaped and arranged together so as to appear substantially as represented in the photograph. Another part of our invention is the design for the rim-plate F, as characterized by its rounded edge g and rows of ornaments h on the rim-plate, as shown in the photograph. Another part of our invention consists of the contour of the section surrounding the fire-pot, as distinguished by the round, straight, downwardly-tapered upper part I and the round, curved, downwardly-tapered lower portion J, combined and arranged together, as shown in the photograph, without regard

to the ornamentation of the parts I and J of the section. Another part of our invention consists of the ornamental open-work configuration k of the upper section I, as shown in the photograph. Another part of our invention consists of the ornamental open-work configuration l of the curved lower section J, as shown in the photograph. Another part of our invention is the design for the base-rim M, as distinguished by the row of ornaments n, shaped and arranged thereon, as represented in the photograph. Another part of our invention is the design for the base P, as distinguished by the rows of ornaments r and border molding f, all shaped and arranged thereon so as to appear as shown in the photograph. Another part of our invention is the design for the damper-frame S, as consisting of the ornaments u, shaped and arranged between and along the openings x, as shown in the photograph. Another part of our invention is the design for the leg T, as shown in the photograph.

What we claim as our invention is—

1. The design for the urn N, as herein described.
2. The design for the urn-base Q, as herein described.
3. The design for the cover R, as herein set forth.
4. The design for the top rim U, as herein described.
5. The design for the upper section X, as described.
6. The design for the rim Z, as shown.
7. The design for the door-frames C, as described.
8. The design for the rim-plate F, as shown.
9. The contour of the section I J, as herein described.
10. The ornamental open-work k in the part I, as shown.
11. The ornamental open-work l in the part J, as shown.
12. The design for the base-rim M, as shown.
13. The design for the base P, as described.
14. The design for the damper-frame S, as set forth.
15. The design for the leg T, as shown.

NICHOLAS S. VEDDER.
FRANCIS RITCHIE.
